UNITED STATES PATENT OFFICE

144,068

DESIGN FOR A BARBER'S CHAIR

Fred J. Piotraschke, Clayton, Mo.

Application April 2, 1945, Serial No. 118,830

Term of patent 14 years

(Cl. D15—3)

To all whom it may concern:

Be it known that I, Fred J. Piotraschke, a citizen of the United States of America, residing at Clayton, in the county of St. Louis, and State of Missouri, have invented a new, original, and ornamental Design for a Barber's Chair, of which the following is a specification, reference being had to the accompanying drawings, forming a part thereof.

In the drawings:

Figure 1 is a perspective view looking from the front of a barber chair embodying my new design;

Figure 2 is a perspective view looking from the

front of the barber chair in raised and reclining position.

Figure 3 is a perspective view looking from the rear of the barber chair in raised position and with the headrest removed;

Figure 4 is a view looking directly at the rear of the barber chair in lowered position and with the headrest in lowered position;

Figure 5 is a view looking directly at the front of the barber chair in lowered position.

I claim:

The ornamental design for a barber's chair, as shown.

FRED J. PIOTRASCHKE.
